UNITED STATES PATENT OFFICE.

FREDERICK GRINNELL, OF PROVIDENCE, RHODE ISLAND.

APPARATUS FOR EXTINGUISHING FIRES.

SPECIFICATION forming part of Letters Patent No. 269,205, dated December 19, 1882.

Application filed March 9, 1881. (Model.)

To all whom it may concern:

Be it known that I, FREDERICK GRINNELL, of the city of Providence, county of Providence, and State of Rhode Island, have invented a new and useful Improvement in a System for Extinguishing Fires; and I hereby declare that the following is a full, clear, and exact description of the same, reference being had to the accompanying drawings, forming part of this specification.

This invention has reference to an improvement in a system of pipes distributed through a building for the purpose of extinguishing any accidental fire that may occur, and thus protecting the building and its contents.

The invention consists in the use of an automatic device by which the air is discharged from the supply main or mains and the waste of water prevented, as will be more fully set forth hereinafter.

In large manufacturing establishments the system of pipes and sprinklers, whether the same are automatic in their action or have to be operated by hand, are usually supplied with water from a fire or force pump, which is usually located at some distance from a large part of the works, and preferably outside the buildings. The pipes leading from the pump to the system of extinguishers or sprinklers are at all times full of air, which, when the pump is started, is forced into the system of pipes, and in an automatic system has to be forced through the one, two, or more distributors that have been opened by the fire. Such a large quantity of air forced through one or a few distributors would require a long time to be discharged, and while adding air to the fire would prevent the water from reaching the same. Instead, therefore, of extinguishing the fire, it would assist the same. To relieve the pipes of the air and automatically close the outlet when the air is discharged, I supply such a system of pipes with one or more air-traps.

Figure 1 is a perspective view of a building provided with a system of pipes and automatic fire-extinguishers, the supply-main being shown provided with an air-trap. Fig. 2 is a sectional view of one form of air-trap, shown open for the discharge of air in solid lines and closed in broken lines. Fig. 3 is a view, partly in section, showing the outlet-port and stem on which

the air-trap is supported. Fig. 4 is a view, partly in section, of a modified form of air-trap and the connecting-pipes.

Similar letters of reference indicate corresponding parts.

In the drawings, A A represent the different stories of a building protected by a system of automatic fire-extinguishers. B is the rising main, and C C are the lateral mains, through which the water is forced to the distributors. D is the supply-main, E the air-trap, and F a check-valve. The whole represents a system in which water is kept in the pipes supplied by a tank, and in which after an alarm has been given the fire-pump is started to furnish the main supply of water.

A system of automatic fire-extinguishers may consist of a system of pipes containing neither water nor air under pressure, and in which the water is forced into the pipes after an alarm has been given, the automatic portion of the system consisting in the distributors near the fire being open and all the rest closed, so that all the water is concentrated on the fire. In such a system the air-trap would be located at the upper end of the rising main B, or at the end of the lateral mains C, so that the air would be discharged first, and as soon as the water would reach the air-trap the outlet would be closed, and the whole force of the water concentrated on the fire. A system of open sprinklers may also be relieved of the air by means of an air-trap.

Referring now to Fig. 2, representing the air-trap E, a is a pipe, on the end of which a stem provided with a port is made to support the air-trap, so that a partial rotation on the stem b will open or close the outlet. d is a hollow arm, communicating with the vessel e, at the upper end of which the outlet f is provided, the lower end being provided with a valve or petcock to discharge the water. The supply-vessel is counterbalanced by the adjustable weight h, placed on the arm g, and secured by a clamp-screw.

The operation of this air-trap is as follows: In its usual position the weight h counterbalances, or, it may be, more than counterbalances, the vessel e, a stop being provided, so that the balance-weight will keep the open arm d opposite the port c, allowing the air to escape by

the opening *f*. As soon, however, as the water reaches the port *f* it will flow into the vessel *e*, and, soon overcoming the weight of the balance-weight *h*, will tilt the vessel and close the port, so that any desired pressure may now be maintained in the pipes.

The air-trap shown in Fig. 4 consists in a valve, *i*, suspended below the pipe *D*, the stem of which is connected with the vessel *K* at *l*. The mouth *m* of this vessel is made large, so that the air issuing from the valve *i* can escape freely. When, however, the water reaches the air-trap, it will pass through the valve into the vessel *K*, and the weight of the water will soon overbalance the counterbalance-weight *h* and close the valve, as is shown in broken lines in Fig. 4.

To prevent the water that may accumulate in the pipe *D* by reason of the leakage of the valves from running into the air-trap and closing the same, the chamber *g* is placed preferably one on each side of the air-trap, to receive such water from leakage, and a valve or outlet is provided at or near the bottom, by which the water can be readily discharged.

Having thus described my invention, I claim as new and desire to secure by Letters Patent—

1. In combination with a system of pipes arranged in a building for extinguishing fires, an air-trap constructed to relieve the system,

upon the advance of the water, of the bulk of air normally contained therein, substantially as before set forth, whereby but little air requires to be expelled through the opened distributor or distributor.

35

2. The combination, with a system of pipes and distributor supplied by the pipes, of one or more normally-open air-traps, through which the advancing water discharges the bulk of the air from the pipes, and which close automatically when the water is discharged, as described.

40

3. The combination, with the pipes *B*, *C*, and *D*, of the air-trap *E*, constructed to remain open for the discharge of the bulk of the air normally contained in the system, and to close when water is being discharged, as described.

45

4. An air-trap consisting of a discharge-opening for the air or water, a valve kept open by means of a counterbalance-weight, and a vessel arranged to receive the discharging water, constructed to close the valve when sufficient water has entered the vessel to overbalance the counterbalance-weight, as described.

50

In witness whereof I have hereunto affixed my name.

FREDERICK GRINNELL.
